(57) **CLAIM**

The ornamental design of the noise reducing filter end cap for a hair dryer, as shown and described.

DESCRIPTION

FIG. 1 is a perspective view of the noise reducing filter end cap for a hair dryer in accordance with the principles of the present disclosure illustrated mounted to a hair styler apparatus;

FIG. 2 is a front perspective view of the noise reducing filter end cap for a hair dryer;

FIG. 3 is a rear perspective view of the noise reducing filter end cap for a hair dryer;

FIG. 4 is a front axial view of the noise reducing filter end cap for a hair dryer;

FIG. 5 is a first side elevation view of noise reducing filter end cap for a hair dryer;

FIG. 6 is a second side elevation view of noise reducing filter end cap for a hair dryer;

FIG. 7 is a third side elevation view of the FIG. 5 is a first side elevation view of noise reducing filter end cap for a hair dryer; and,

FIG. 8 is a rear axial view of the noise reducing filter end cap for a hair dryer.

Any portions of the figures shown in broken lines are for illustrative purposes only and form no part of the claimed design.

1 Claim, 8 Drawing Sheets
